UNITED STATES PATENT OFFICE

111,113

DESIGN FOR A MONKEY DOLL

Emma Valentine, Milwaukee, Wis., assignor of one-third to Kathryn Egan, Milwaukee, Wis.

Application May 16, 1938, Serial No. 77,204

Term of patent 3½ years

To all whom it may concern:

Be it known that I, Emma Valentine, a citizen of the United States and resident of Milwaukee, in the county of Milwaukee and State of Wisconsin, have invented a new, original, and ornamental Design for a Monkey Doll, of which the following is a specification, reference being had to the accompanying drawing, forming part thereof.

The figure is a perspective view of the monkey doll, showing my new design.

I claim:

The ornamental design for a monkey doll, as shown.

EMMA VALENTINE.
